(57) **CLAIM**

I claim the ornamental design for a cord stanchion device, as shown and described.

DESCRIPTION

A portable barrier device used for crowd management, customer guidance, hospitality, safety and the like.

FIG. 1 is a perspective view of a cord stanchion device.

FIG. 2 is a front elevation view of a cord stanchion device.

FIG. 3 is a rear elevation view of a cord stanchion device.

FIG. 4 is a right side elevation view of a cord stanchion device.

FIG. 5 is a top plan view of a cord stanchion device.

FIG. 6 is a bottom plan view of a cord stanchion device; and,

FIG. 7 is an exploded perspective view of a cord stanchion device.

The broken lines are for illustrative purposes only and form no part of the claimed design.
